poration of Delaware

Application June 10, 1950, Serial No. 167,335

4 Claims. (Cl. 121—20)

1

My present invention relates in general to improvements in hydraulic machines, and relates more particularly to various improvements in the construction and operation of hydraulically actuated reciprocable impact motors of the type covered generally by my Patent No. 2,512,763, granted June 27, 1950.

In my prior patent above identified, I have shown an improved hydraulically actuated portable impact motor embodying a differential piston reciprocable by liquid under pressure with the aid of a balanced valve which is rotatable to automatically alternately admit pressure liquid to the opposed piston faces, and a resilient or pneumatic cushion for storing energy delivered by the piston while travelling in one direction and for returning the stored power to the piston so as to deliver powerful impact blows when moving in the opposite direction. The rotation of the automatic valve of this prior impact machine was effected by an auxiliary rotary hydraulic motor driven by liquid under pressure from the same source which supplied actuating liquid to the piston of the main motor; and the timing of the valve and of the pneumatic cushion was such that pressure liquid was admitted to the smaller face of the differential piston and was released from the opposite larger face thereof precisely when the cushion attained its maximum power or energy storing position.

While this prior impact assemblage was highly successful and superior to previous hydraulic hammers in operation, the portable unit was relatively bulky and cumbersome to manipulate and the construction of the hammer employing a double acting piston and the location of the rotary automatic control valve made it rather difficult to insure accurate timing and also introduced complications in production and assembly of parts. Then too, since these portable impact units are utilized under widely varying temperature conditions which may detrimentally affect accurate timing and functioning of the control valve, the previous device did not make adequate provision for automatically compensating for such temperature variations in the actuating liquid which travels in a closed circuit, and more than one hammer could not be effectively operated from the same liquid supply source. In addition to these objections and deficiencies, the prior impact motors could not be readily actuated to deliver either light or heavy blows at the will of the operator, and since oil is ordinarily employed in these hammers no positive provision was made for utilizing escaping oil to best advantage and for preventing messy conditions.

2

It is therefore a primary object of the present invention to provide various improvements in the construction and operation of such reciprocable hydraulic impact motors whereby the structure is materially simplified and the functioning thereof is vastly improved.

Another important object of this invention is to provide an improved portable hydraulically actuated impact unit comprising a reciprocable power piston and an automatically functioning valve for controlling the delivery of liquid to and from the piston, wherein the control valve is formed and disposed to produce impact blows of maximum intensity and with minimum vibration of the unit.

A further important object of the invention is to provide a light but powerful reciprocable impact motor comprising relatively few simple, and compact and durable parts which may be quickly and conveniently assembled or dismantled, and which function automatically with utmost precision and dependability.

Still another object of my invention is to provide an improved hydraulic impact assemblage in which the temperature of the power transmitting liquid may be effectively automatically controlled to insure uniform speed and most efficient operation of the system, and which is readily operable to deliver either light or heavy blows or impacts of any desired intensity.

An additional object of the present invention is to provide an improved oil actuated impact motor wherein leakage liquid is prevented from messing the exterior of the unit, and may be utilized to lubricate various parts of the equipment.

Another object of my present invention is to provide an improved portable hydraulically actuated powerful impact tool and system, which is simpler and less expensive than that shown in my prior patent, and in which several hammers may be effectively operated from a common closed fluid supply circuit.

These and other objects and advantages of the present invention will be apparent from the following description.

A clear conception of the several features involved in my present improvement, and of the construction and operation of a typical portable hydro-pneumatic hammer embodying the invention, may be had by referring to the drawings accompanying and forming a part of this specification wherein like reference characters designate the same or similar parts in the various views.

Fig. 1 is a longitudinal central section through one of the improved reciprocable hydraulic im-

compact motors and its resilient pneumatic cushioning device, showing the differential piston and the cushioning plunger in impact delivery position in solid lines and the latter in its opposite extreme position in dot-and-dash lines;

Fig. 2 is a side elevation of the portable power unit shown in Fig. 1 looking toward one of the air filters for the pneumatic cushioning device;

Fig. 3 is an enlarged transverse section through the rotary automatic liquid flow control valve of the unit, taken along the line 3-3 of Fig. 1 and showing the valve in piston up-stroke position;

Fig. 4 is a similarly enlarged transverse section through the rotary automatic liquid flow control valve, also taken along the line 3-3 of Fig. 1 but showing the valve in piston down-stroke or impact delivery position;

Fig. 5 is a likewise enlarged transverse section through the reciprocable power unit taken along the line 5-5 of Fig. 1;

Fig. 6 is a somewhat more enlarged transverse section through the thermostatic control device for the valve impelling rotary motor of the improved impact assemblage, taken along the line 6-6 of Fig. 1 and showing the automatic temperature actuated motor speed control;

Fig. 7 is an enlarged central vertical section through the manually actuated liquid flow regulating valve of the type shown in Fig. 1, but showing this valve set for delivery of light blows;

Fig. 8 is a likewise enlarged central vertical section through a modified type of manually actuated liquid flow regulating valve, likewise showing the same set for light blows; and

Fig. 9 is a partially exploded diagram showing a typical liquid supply and circulating system for actuating and controlling the liquid flow.

The gist of my present invention is the provision of a compact but powerful hydro-pneumatic hammer having an impact delivery piston cooperating with a pneumatic blow augmenting cushion and provided with differential opposite faces the smaller of which is constantly exposed to pressure liquid from a closed circulatory system while the larger is alternately exposable to fresh pressure liquid from the supply system together with pressure liquid from the smaller face during impact strokes and to exhaust during the return strokes, and a simple constantly rotating automatically functioning valve disposed coaxially of the power piston for controlling the flow of liquid to and from the piston faces so as to produce impact blows of maximum intensity without introducing excessive vibration in the liquid circulating system. While the invention has been shown by way of illustration as being advantageously applicable to a universally movable portable hammer employing oil as the actuating liquid and having the control valve operable by a rotary hydraulic motor, it is not the intent to thereby unnecessarily restrict the utility of the improved features; and it is also contemplated that specific descriptive terms employed herein be given the broadest possible interpretation consistent with the disclosure.

Referring to the drawings, the typical portable hydro-pneumatic hammer shown therein comprises in general a composite elongated main casing consisting of aligned and coaxial sections 10, 11, 12, 13, 14 firmly but detachably interconnected by bolts 15 and compression springs 16; a hydraulic power piston 17 reciprocable within a bore 18 formed in a cylinder sleeve 19 mounted centrally within the casing section 11, and having

a large impact or upper face 20 and a smaller annular retracting or lower face 21 surrounding its piston rod 22; a single automatic annular rotary liquid flow control valve 23 journaled in the casing section 11 in axial alignment with the bore 18 and being constantly rotatable by a rotary hydraulic motor 24 housed within the casing section 10; a manually operable flow regulating valve 25 slidably confined within a housing 26 secured to the casing section 11 and being operable by means of a lever 27 and an arm 28 pivotally associated with one of the hammer manipulating handles 29 which are formed integral with the casing section 10; a pneumatic cushioning plunger 30 slidably confined within a bore formed in the casing section 12 and being flexibly secured to the main piston rod 22; an impact transmitting plug 31 slidably confined within a central bore formed in the casing section 13, and projecting into the path of travel of the plunger 30; and an impact tool or implement 32 detachably and slidably confined within the casing section 14 in alignment with the plug 31.

The upper casing section 10 is formed as a cap 25 snugly embracing the upper portion of the cylinder section 11 and likewise embracing a partition 33 which segregates the automatic control valve 23 from its propelling motor 24. The single annular valve 23 is adapted to be constantly rotated at high speed by the rotor of the hydraulic motor 24 through a shaft 34 journaled in the partition 33, and the valve 23 has a pair of diametrically opposed radial ports 35 which are inwardly in open communication with the larger upper face 20 of the power piston 17, and this valve must be totally balanced at all times. The control valve 23 is rotatable within a stationary bushing 36 secured to the casing section 11 and having therein two accurately formed sets of opposed passages 37, 38 of which the passages 37 are of less circumferential width than the passages 38 and the former communicate with high pressure liquid conduits 39 while the latter likewise communicate with the low pressure conduits 40, see Figs. 1, 3 and 4.

In order to effectively balance the pressures acting upon the valve 23, the opposite end surfaces of this valve are constantly connected to the valve interior and to the upper piston displacement chamber through openings 43, as shown in Fig. 1. The cylinder sleeve 19 is fixedly secured to the casing section 11, and in order to prevent dangerously high pressures in the upper cylinder chamber, the upper extremity of the sleeve 19 is provided with cut-outs 41 which communicate with the high pressure conduits 39 past spring pressed ball relief valves 42, as shown in Fig. 5.

Liquid under pressure is normally admitted to the valve driving motor 24 from the high pressure conduits 39 through a duct 45, and spent liquid is exhausted from the rotor of the motor 24 through a duct 46, and in order to maintain the speed of the auxiliary motor rotor constant it is necessary to retain the flow of propelling liquid sufficient to maintain the desired speed. Since oil is preferably utilized as the actuating liquid, this oil will thin out and flow more readily when warm than when cold, and the temperature of the liquid delivered to the motor 24 may therefore be utilized to regulate the speed of the motor rotor either at the motor itself; or at some other locality in the liquid circulating system. As illustrated in Figs. 1 and 6, a needle valve 47 is disposed in the high pressure inlet duct 45 of the

motor 24, and the needle valve 47 is movable in one direction by a bellows 48 surrounded by fluid which is expansible when heated to close the needle, and is positively movable in the opposite direction by a helical compression spring 49 to open the needle, more or less. When the oil is warm less liquid will pass through the motor 24 than when cold, but the bellows 48 and spring will automatically compensate for variations in temperature or fluency of the oil so as to maintain substantially constant speed of revolution of the automatic valve 23.

This speed of rotation of the automatic valve 23 may also be controlled by maintaining constant viscosity of the oil in a closed system with the aid of mechanism such as illustrated in Fig. 9 and without utilizing a bellows and spring actuated needle valve 47 in the unit itself. In this modified system, a constant pressure variable delivery pump 50 is driven by an internal combustion engine 51 having an oil cooler 52 associated therewith, and the pump 50 has an intake line 53 communicable with a supply reservoir 54 provided with an inlet pipe 55 and also has a flexible discharge line 56 connected to the high pressure conduits 39 of the hydraulic hammer unit. The exhaust pipe 57 of the engine 51 has two branches 58, 59 one of which passes through the oil 60 within the reservoir 54 and the other of which leads to the atmosphere, and the flow of hot exhaust gases through these branches 58, 59 is controllable by a flap valve 61. The reservoir inlet pipe 55 also has two branches 62, 63 one of which passes through the cooler 52 and the other of which is flexible and communicates with the exhaust conduits 40 of the portable impact unit, and the flow of liquid through these return branches 62, 63 is controllable by another flap valve 64. The flap valves 61, 64 are movable by a thermostat 65 which is activated by a bulb 66 disposed within the oil 60 in the reservoir 54 in a manner to be specifically explained later on.

The manual regulating valve may be either of two types, and as shown in Figs. 1 and 7, the housing 26 of the manually operable flow shut-off and regulating valve 25 may be secured directly to the side of the casing section 11 through an opening in the section 10, and the valve 25 which is located in the high pressure conduit 39 is of the reciprocating piston type and is totally balanced by virtue of the fact that its opposite ends are connected to the low pressure conduit 40 while its medial portion is recessed to provide annular opposed faces exposable to the high pressure conduit 39 only when the valve is opened. As previously indicated, the regulating valve 25 is adapted to be opened more or less by means of the lever 27 and arm 28, but this valve 25 is constantly urged toward closed position relative to both the pressure and exhaust lines by a spring 68 coacting with its end remote from the valve stem 69. The lever 27 is swingably suspended from the casing section 10 by a pivot 70 and has a slot cooperable with a pin 71 so as to limit the swinging motion thereof, and the arm 28 is swingably suspended within one of the handles 29 by another pivot 72 and coacts with the valve stem 69 and with a horn 73 formed integral with the lever 27. The handles 29 may also be provided with suitable gripping coverings 74 and one of these handles serves to protect the adjacent regulating valve assembly. The flow regulating valve 25' of Fig. 8 is different from that shown in Fig. 7, since it connects the conduits 39, 40 with each other when the hammer is

inactive, and this permits free circulation of the oil 60.

When operating these portable hammer units it is frequently desirable for the operator to regulate the intensity of the blows delivered to the tool 32 and to be able to deliver light blows when performing certain types of work where normal heavy blows might be destructive. In order to permit such operation the valve 25 or 25' is provided with a chamfer 75 which enables the operator to gradually increase the intensity of the impacts when starting, or to maintain light blow intensity by merely holding the lever 27 down to a limited extent. Such operation will cause the chamfer 75 to throttle the flow of liquid delivered to the piston 17 to any desired extent thus resulting in blows of variable intensity.

The piston rod 22 is guided for reciprocation in a sleeve bearing 77 confined within the lower end of the casing section 11 in axial alignment with the cylinder sleeve 19, and this bearing 77 is lubricated by leakage oil from the upper cylinder chamber. An annular groove 77' in the bearing 77 communicates with one or more low pressure passages 38 through a duct 78, see Fig. 1, and serves to return the leakage oil. Thus, only a small amount of leakage oil is passed for the lubrication of the pneumatic cylinder and other moving parts. The pneumatic plunger 30 which is slidably confined within a bore of the casing section 12, is flexibly connected to the lower extremity of the piston rod 22 by means of a universal joint 79, and this plunger 30 is cooperable with air inlet and exhaust ports 80 to confine and compress air in a cushioning chamber 81 formed between the casing section 11 and the plunger within the upper portion of the section 12 whenever the plunger rises. The ports 80 are communicable with the ambient atmosphere through a pair of air filters 82 removably confined within pockets formed in the casing section 12 by perforated plates 83 swingably secured to the section 12 and which are held in closed position by spring retainers 84. The casing section 13 within which the motion transmitting plug 31 is slidably confined, has lubricant conducting passages 85' formed therein and cooperating with similar passages in the section 12 for conducting leakage oil 60 from the bearing 77 to the plug 31 and implement 32 without permitting such oil to escape to the exterior of the main casing body, and the tool or implement 32 may be detachably secured to the lowermost casing section 14 by means of a spring pressed latch 85, as illustrated in Fig. 1.

When the improved hydro-pneumatic impact units have been properly constructed and assembled as shown and described, they may be utilized either singly or in multiple in connection with systems utilizing either constantly or intermittently operable pumps or other sources of supply wherein the oil is circulated either constantly or at will. If the hammer units are associated with a system embodying a constant pressure variable delivery pump 50 as in Fig. 9, the type of regulating valve 25 shown in Figs. 1, 7 and 9 should be utilized, and with this type of valve 25 the flow of oil 60 through the flexible pipes 56, 63 will be interrupted when the corresponding unit is not in use and the lever 27 thereof is released. However, if a constant liquid delivery is utilized, a modified flow regulating valve of the type shown in Fig. 8 should be employed, and this valve 25' will permit free circulation of the oil 60 through the supply and discharge pipes

56, 63 of each hammer unit when inactive and the lever 27 thereof is released.

In either case, when the lever 27 of a portable hammer is depressed, liquid under high pressure will be admitted to the conduits 39 of the corresponding unit and will revolve the rotor of the motor 24, thereby constantly rotating the balanced automatic control valve 23 and at high speed, and liquid under high pressure is always admitted to the lower smaller face 21 of the differential power piston 17 as soon as the valve 25 or 25' is opened. Whenever the rotary control valve 23 reaches the position shown in Fig. 3 with the ports 35 communicating with the larger or wider passages 38 and with the low pressure conduits 40, then the larger piston face 20 will be exposed to exhaust and the high pressure liquid constantly acting upon the smaller piston face 21 will move the piston 17 and the air compression plunger 30 upwardly to cause the latter to confine and compress air within the cushioning chamber 81. At the instant when the piston 17 and plunger 30 reach the upper end of their upstroke, the automatic valve 23 will have advanced toward the position shown in Fig. 4 so as to connect the upper piston face 20 with the high pressure conduits 39 and with the upper piston displacement chamber through the ports 35 and smaller passages 37; whereupon the high pressure liquid will cooperate with the pneumatic energy stored within the chamber 81, to cause the plunger 30 to deliver a sharp impact blow to the implement 32 through the plug 31.

This cycle of operations will be rapidly repeated during continued rotation of the valve 23, and the liquid 60 will flow constantly in the same direction through the conduits 39, 40 as long as the regulating valve 25 is held in open position; and by properly manipulating the valve 25 as above described the hammer unit may be caused to deliver either light or heavy blows to the tool 32. If the automatic speed control for the auxiliary valve driving motor 24 shown in Figs. 1 and 6 is utilized, the fluid coating with the bellows 48 will adjust the needle valve 47 in accordance with variations in the temperature of the oil 60 flowing through the motor 24 so as to maintain the motor speed substantially constant, and this speed regulating device may be utilized in conjunction with any type of liquid circulation but does not necessarily affect the viscosity or fluency of the oil by heating or cooling the same.

However, the speed of the hammers may also be regulated by maintaining constant viscosity of the actuating liquid and by utilizing a system such as shown in Fig. 9 whereby the oil may be either heated or cooled to suit. In this automatic viscosity control system, the constant pressure variable delivery pump 50 may simultaneously operate one or more impact units past regulating valves 25, and the flap valves 61, 64 will be automatically adjusted by the thermostat 65 to cause more or less cooling or heating of the liquid. When the oil 60 in the power system is hot and highly fluent, the valve 61 will be positioned as shown in solid lines to cause the hot engine exhaust gases to escape directly to the atmosphere through the branch pipe 59, and the other valve 63 will be positioned as shown in dot-and-dash lines to cause the oil returning from the impact unit to travel through the cooler 52 and to become less fluent. If the oil 60 is too cold and not sufficiently fluent, the valve 61 will

be positioned as shown in dot-and-dash lines and the other valve 63 will be positioned as shown in solid lines, thereby causing the cooler 52 to be cut out and the exhaust from the engine 51 to travel through the branch pipe 58, thus heating the liquid and increasing its fluency. This improved system therefore functions to automatically control the viscosity of the oil so as to maintain constant speed of the motor 23, thus providing great flexibility in operation of the hammers and effective functioning thereof in hot and cold regions.

From the foregoing detailed description of the construction and operation of my improved reciprocable impact motor and system, it should be apparent that I have in fact provided a hydro-pneumatic hammer unit which is simple, compact and durable in construction, and which is moreover highly efficient in use and flexible in its adaptations. The unit embodies only a single simple automatic valve 23 and a single simple manual flow regulating valve 25 in order to actuate the same so as to produce impacts of desired intensity desirable for performing various classes of work, and by locating the motor 24, valve 23, piston 17, plunger 30 and plug 31 in axial alignment within axially separable and aligned casing sections, all of these parts may be quickly and conveniently assembled or dismantled for inspection. The annular valve 23 and its confining bushing 36 may be accurately machined so as to operate with utmost precision in producing maximum blows; and by causing the oil 60 to constantly flow in the same direction through each portable unit, vibration is reduced to a minimum and annoyance to the operators is minimized.

The speed of the motor 24 can be selected or set manually with the aid of the needle valve 47, and is maintained by the thermostat 65. This reduces the manipulator's effort to a minimum. The use of the valve 25 permits any desired numbers of the individual units to be operated by a single constant pressure, variable delivery pump, while valve 25' is preferably used in conjunction with constant delivery pumps for units requiring only one hammer. The present improved units are therefore entirely automatic in operation except for the actuation of the starting and stopping lever 27, and may be effectively operated in extremely hot or cold weather. All valves are not only accurately timed but are also automatically balanced, and escaping oil is also utilized to advantage for lubrication purposes. The improved portable units may be manufactured at moderate cost in various sizes for diverse uses, and are capable of delivering powerful impacts considering their compactness.

It should be understood that it is not desired to limit this invention to the exact details of construction or to the precise mode of operation of the typical hydraulic impact units herein shown and described, for various modifications within the scope of the appended claims may occur to persons skilled in the art.

I claim:

1. In a hydraulically actuated reciprocable impact motor, a casing having a bore; a piston reciprocable within said bore and having opposed faces exposable to liquid under pressure, a rotary valve associated with said casing and being automatically operable to admit said liquid to said piston faces, a rotary motor operable by the pressure liquid to actuate said valve, and a thermostat operable by variations in the temperature of

said liquid admitted to the piston through said valve for automatically varying the speed of rotation of the valve by regulating the speed of said motor.

2. In a hydraulically actuated reciprocable impact motor, a casing having a bore, a piston reciprocable within said bore and having differential opposed faces exposable to liquid under pressure, a valve associated with said casing and being automatically rotatable about the axis of said piston to admit said pressure liquid to the opposed piston faces and from the smaller to the larger face, a rotary motor operable by said liquid to rotate said valve, and a thermostat operable by variations in the temperature of said liquid for passing through said valve for automatically regulating the speed of said motor in accordance with variations in the viscosity of the liquid.

3. In a hydraulically actuated reciprocable impact motor, a casing having a bore, a piston reciprocable within said bore and having differential opposed faces the smaller of which is constantly exposed and the larger of which is alternately exposable to liquid under pressure, a rotary valve associated with said casing and being automatically rotatable about the piston axis to admit liquid to the opposed piston faces, a rotary motor operable by said pressure liquid to rotate said valve, a thermostat operable by variations in temperature of the liquid passing through said valve for maintaining uniform selected speed of said motor and reciprocation of the piston, and means for manually regulating the flow of liquid to said automatic valve to vary the selected speed of movement and the intensity of the impacts delivered by said piston.

4. In a hydraulically actuated reciprocable impact motor, a casing having a bore, a piston reciprocable within said bore and having opposed faces one of which is alternately exposable to liquid under pressure and to exhaust while the other is constantly exposable to said pressure liquid, a rotary valve associated with said casing beyond one end of said piston and being rotatable to admit liquid under pressure to both of said faces and to alternately exhaust said one face, a rotary motor operable by said pressure liquid to constantly rotate said valve, and a thermostatically controlled valve confined within said casing and being operable by variations in the temperature of the liquid admitted to said piston past said rotary valve to automatically vary the speed of rotation of said motor.

CARL A. BERGMANN.
